CLAIM

The ornamental design for an illuminated control device, as shown and described.

DESCRIPTION

FIG. 1 is a front perspective view of an illuminated control device showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view of a second embodiment thereof;

FIG. 8 is a front view thereof;

FIG. 9 is a left side view thereof;

FIG. 10 is a right side view thereof;

FIG. 11 is a top view thereof; and,

FIG. 12 is a bottom view thereof.

(Continued)

The drawings include shadows and reflections which indicate contour, not surface ornamental, and form no part of the claimed design.
